UNITED STATES PATENT OFFICE.

ISAAC H. WEINBERG AND CHARLES F. BISBING, OF NEW YORK, N. Y.

UMBRELLA AND PARASOL.

1,352,332.

Specification of Letters Patent. Patented Sept. 7, 1920.

Application filed March 5, 1920. Serial No. 363,606.

To all whom it may concern:

Be it known that we, ISAAC H. WEINBERG and CHARLES F. BISBING, both citizens of the United States, and residents of the city 5 of New York, borough of Manhattan, in the county of New York and State of New York, have invented a new and Improved Umbrella and Parasol, of which the following is a full, clear, and exact description.

10 This invention relates to improvements in umbrellas and parasols, an object of the invention being to provide a convenient attachment which operates to hold the ribs of the umbrella or parasol close to the handle. 15 and which also provides a convenient means for supporting the umbrella or parasol on the wrist or arm of the user.

A further object is to provide an attachment of the character stated, which can be 20 conveniently located on any ordinary parasol or umbrella and which not only adds to the convenience of carrying the umbrella, but also is ornamental and attractive in appearance.

25 With these and other objects in view the invention consists in certain novel features of construction, and combinations and arrangements of parts as will be more fully hereinafter described and pointed out in the 30 claims.

The accompanying drawing is a view in elevation illustrating in full lines one position of our improved attachment and in dotted lines another position of the same.

35 1 represents the handle and 2 the cover of an umbrella or parasol, the latter having the ordinary ribs 3 which when the umbrella or parasol is closed, are located around the lower end of the handle or adjacent thereto.

40 4 represents an ornamental band which may be of metal or any other suitable material and which is secured around the handle 1 and provided with an eye 5 supporting a link 6. An ornamental cord 7 is secured to the link 6 and is connected by means of a link 8 with a ring 9, said ring having an eye 10 receiving the link 8. The cord may be 45 ornamented by having a tassel 11 at its free end and is preferably of a color conforming 50 to the color of the umbrella cover, although,

of course, this is purely a matter of taste and may be varied to suit the trade.

The ring 9 is of a diameter to snugly fit around the cover 2 adjacent the ends of the ribs 3 and hold the cover around the handle 55 preventing the ribs from flying out and making the carrying of the umbrella a convenient one.

It will be noted that the cord 7 is of a sufficient length between the band 4 and the 60 ring 9 to provide a loop to receive the arm of the user so that the umbrella or parasol can be conveniently carried on the arm. When it is desired to raise the umbrella, the ring 9 is moved upwardly onto the handle 1, 65 and it will be noted that the handle 1 is tapering in form; that is, it decreases in diameter toward its lower end so that when the ring 9 is forced up onto the handle 1, it will frictionally bind on the handle and 70 hold the parts in the position illustrated in dotted lines.

We would have it understood that while it is our purpose to provide the band 4 and the ring 9 of metal, celluloid, or other similar ornamental material and provide a cord which is of a material and color which conforms to the color of the umbrella cover, we 75 do not limit ourselves in these particulars, but consider ourselves at liberty to make 80 such changes and alterations as fairly fall within the spirit and scope of the appended claims.

We claim:

1. The combination with an umbrella or 85 parasol having a handle thereon, of a ring movable longitudinally of the handle and adapted to be supported on the handle or around the ribs of the umbrella or parasol, a flexible device secured at one end to the 90 handle and at its other end to said ring, said flexible device of a sufficient length between its point of connection with the handle and the ring whereby an arm receiving loop is provided in either position of the ring, and 95 said handle tapering in form and adapted to support the ring thereon by a frictional engagement therewith.

2. The combination with an umbrella or 100 parasol having a handle thereon, of a ring

movable longitudinally of the handle and adapted to be supported on the handle or around the ribs of the umbrella or parasol, a flexible device, and a ring fixedly secured 5 to the handle and to which said flexible device is connected, said flexible device being also connected to the first-mentioned ring and of a sufficient length between the rings

whereby an arm receiving loop is provided in either position of the ring, said handle 10 tapering in form and adapted to support the ring thereon by a frictional engagement therewith.

ISAAC H. WEINBERG.
CHARLES F. BISBING.
